TEXTILE LOOMS
Walter Scheffel, Industriestrasse 53, Weissenburg,
Bavaria, Germany
Filed May 20, 1960, Ser. No. 30,476
Claims priority, application Germany May 25, 1959
9 Claims. (Cl. 139—127)

The present invention relates to improvements in textile looms, and more particularly to an improvement in textile looms having pneumatic picking systems.

The usual textile looms having pneumatic picking systems are disadvantageous since only fabrics of limited width can be produced on such looms. Furthermore, the yarn breakage is high in such looms.

Looms having a pneumatic picking system according to the present invention, however, permit the production thereon of wide fabrics. Moreover, the present invention substantially reduces the risk of yarn breakage. Also, the performance of the loom is greatly improved. Finally, despite the use of a shuttleless pneumatic picking action, firm selvages can be formed along the fabric edges.

It is, therefore, an object of the present invention to provide an improved textile loom having pneumatic picking systems.

It is a further object of the present invention to provide an improved textile loom having a pneumatic picking system upon which wide fabrics may be produced.

In order that the present invention may be more readily understood reference will now be made to the accompanying drawings in which:

FIGURE 1 is a schematic representation of pneumatic equipment in a loom having blow and suction pipes and also air admission elements;

FIGURE 2 is a side view of a device which permits insertion of picks into wide fabrics without the use of pilot pipes;

FIGURE 3 is one form of construction of air admission elements for use with the device illustrated in FIG. 2;

FIGURE 4 is an enlarged detail view of an air admission element according to FIG. 3;

FIGURE 5 is a schematic representation of a modified form of air admission element.

The pneumatic apparatus shown schematically in FIGURE 1 comprises a blower 1, a blow pipe 29, a suction pipe 30 and a connecting pipe 4 extending from suction pipe 30 to the blower 1. The weft thread S is supplied by the bobbin 9. The blower 1 draws in the surrounding air in the direction of arrow B and forces it into the blow pipe 29 in the direction of arrow A maintaining a continuous flow of air, its pressure being only slightly above the pressure of the atmosphere. The weft thread to be fed into the machine runs through a yarn-measuring cone 8. The thread S coming from a cone 9 runs through the yarn brake 14 and is presented at the cone 8 by a weft changer 16. The cone 8 is provided with an entraining member 17 which picks up the weft thread which is presented by the device 16 causing the winding of the thread onto the cone 8. The winding continues until the entraining member which is mounted tiltably at the cone 8, is tilted. This tilting is effected by a control pulse generated once in the course of each revolution by a cam on the main drive shaft of the loom. Upon the tilting of the entraining member 17 the dual level 15 will cause the yarn brake 14' to open and the yarn brake 14 to close. The weft thread S which runs also through the yarn brake 14' can now—because the yarn brake 14' is open—be carried by the air flow coming from the blower 1 to the blow pipe 29 and blown toward the shed. The air issuing from the air admission elements 23 and 24 now impinges upon the thread, supports it, and

2

carries it along in its direction of flight. Moreover, suction pipe 30 applies a suction effect to the weft thread S. These effects in combination constrain the weft thread S to stay in its predetermined trajectory along a considerable width of cloth.

In the device shown in FIGS. 1 to 5 tubes 23 and 24 which serve as air admission means are secured to the sley 22. In their operative position the surfaces of the air admission elements 23 and 24 facing the interior of the shed 25 bear on the warp threads from both sides of the shed.

In longitudinal section the tubes 23 and 24 may have the shape illustrated in FIG. 3. Facing the shed the pipes form nozzles which project saw-tooth fashion. From the faces of the "teeth" 26 and 27 the air admitted through U and V issues in the direction of arrows P and P'. In other words, the nozzles point in a direction for discharge of the air from tubes 23 and 24 in the direction of the travelling weft thread S.

Furthermore, the nozzles are so contrived that the air issuing therefrom will flow in the longitudinal axis of the pick, as indicated by arrows C, D, E and F in FIG. 2. As illustrated more particularly in FIG. 4, the warp threads K rest on the backs 28 of the "teeth."

The blow and suction pipes may be stationary and located on each side of the warp shed as shown schematically in FIGURES 1 and 3.

FIG. 5 shows one of the air admission elements, of which a pair is always provided of a kind suitable for picking from both selvedges of the cloth. The illustrated air admission element is likewise embodied in a tube marked 31. The tube is again formed with saw-tooth nozzles. However, these are now arranged to point alternately to one edge of the cloth and the other. This is clearly shown in FIG. 5 where the "saw-teeth" from which the air issues to the left are marked 32, whereas the "saw-teeth" from which the air issues to the right are marked 33. Moreover, the nozzles are so contrived that the compressed air entering tube 31 from the right or from the left will always issue from the nozzles in the direction of air admission. In other words, the air from V will always issue from nozzles 33 and the air from W will issue from nozzles 32. Consequently, when the direction of air flow through pipe 31 is reversed, the direction of air flow issuing from the air admission elements towards the axis of the trajectory of the weft thread will likewise be reversed. By reversal of the flow direction in the air admission elements and by the simultaneous reversal of the air flow through the suction and blow pipes the insertion of the weft thread can be effected turn and turn-about from each edge of the cloth.

When the weft thread has been carried through the shed it is beaten up by a batten in the conventional manner.

In the illustrated example the nozzles and the admission pipes are of one-piece construction. In a practical embodiment of the invention this is by no means essential. Moreover, there is no necessity for the nozzles to be of saw-tooth pattern, provided they are appropriately contrived to discharge air into the shed towards the longitudinal axis of the weft thread trajectory in the direction of insertion of the pick whilst leaving the warp threads "out side the flow pattern."

It is furthermore, unnecessary to affix the air admission elements to the sley. They may be advanced on to the warp and withdraw independently of the motions of the sley. The path of motion of the air admission elements may be shortened if they do not thus participate in the reciprocation of the sley.

What I claim is:

1. In a loom for producing woven fabrics of a considerable width having a pneumatic picking system com-

prising a blow pipe located adjacent the side of the warp, means for admitting a weft thread to said blow pipe, and means for supplying compressed air to said blow pipe whereby said weft thread is propelled through the shed, the improvement consisting essentially of means for maintaining the weft thread in a predetermined trajectory along a considerable width of fabric comprising at least one air admission element extending across the width of the fabric adjacent to the shedding point, and compressed air being supplied to said element, said air admission element being formed by an air pipe adjacent the shedding point extending outside of the warp threads and transversely thereto adjacent the shedding point, said air pipe including a plurality of nozzles spaced across the width of the fabric and arranged in the faces of the respective teeth formed on said air pipe, said nozzles being arranged to face in the direction of motion of said weft thread with the compressed air passing from said nozzles generating an air current in the direction of motion of the traversing weft thread to maintain the same in its predetermined trajectory across the width of the fabric.

2. A loom according to claim 1, wherein said air admission pipes are movable relative to said warp, the position of said pipes being close to the warp thread during insertion of said weft thread so that the warp threads rest on the backs of the teeth formed on said air admission pipes whereby air can escape from said nozzles to generate said air current.

3. A loom according to claim 1, wherein the faces of the teeth formed on said element all face in the same direction.

4. A loom according to claim 1, further including a sley, and wherein they are a pair of said air admission elements secured to said sley, said elements being arranged on opposite sides of the shed and in the operative position thereof bearing on the warp threads from both sides of the shed.

5. A loom having a pneumatic picking system comprising a pair of pipes, one of said pipes being located on one side of the selvage of the fabric, the other of said pipes being located on the other side of said selvage, said pipes being adapted to selectively operate as a blow pipe for passing a weft thread through the shed from either side thereof along a predetermined trajectory, means for admitting a weft thread to the blow pipe, means for supplying compressed air to the blow pipe whereby said weft thread is propelled through the shed, and means for maintaining the weft thread in its predetermined trajectory across a considerable width of fabric, said last-mentioned means including at least one pair of air admission elements extending across the width of the fabric adjacent to the shedding point, said air admission elements being formed by air pipes extending outside of the shed and transversely over the warp, the side of said air pipes facing the shed being constructed in a saw-tooth manner, said air pipes each including a plurality of nozzles spaced across the width of the fabric and arranged in the faces of the teeth formed on the respective air pipe, said nozzles in one of said air pipes facing in the opposite direction with respect to the nozzles in the other of said air pipes, and means for supplying compressed air to the one of said air pipes having nozzles facing in the direction of motion of said weft thread to generate an air current in the direction of motion of the traversing weft thread to maintain the same in its predetermined trajectory across the width of the fabric.

6. In a loom for producing woven fabrics of considerable width having a pneumatic picking system comprising blow and suction pipes located on either side of the warp threads of the fabric, means for admitting a weft thread to said blow pipe, and means for supplying compressed air to said blow pipe whereby said weft thread is propelled through the shed, the improvement consisting essentially

of means for maintaining the weft thread in a predetermined trajectory along a considerable width of fabric comprising at least one air admission element extending across the width of the fabric adjacent to the shedding point, and compressed air being supplied to said element, said air admission element being formed by an air pipe extending outside of the warp threads and transversely thereto adjacent the shedding point, said air pipe including a plurality of nozzles spaced across the width of the fabric for directing air toward the trajectory of said traversing weft thread in the direction of travel of the weft thread to generate an air current in the direction of the motion of the traversing weft thread to maintain the same in its predetermined trajectory across the width of the fabric.

7. A loom according to claim 6, wherein the loom includes a reed, said air admission elements being separated from the reed and wherein said air admission pipes are adjusted to a position means for adjusting the position of said elements in such a manner that they may be brought close to the warp threads at least when inserting the weft threads.

8. A loom having a pneumatic picking system comprising a pair of pipes, one of said pipes being located on one side of the selvage of the fabric, the other of said pipes being located on the other side of said selvage, each said pipe being adapted to selectively operate as a blow pipe for passing a weft thread through the shed from either side thereof along a predetermined trajectory, means for admitting a weft thread to the blow pipe, means for supplying compressed air to the blow pipe whereby said weft thread is propelled through the shed, and means for maintaining the weft thread in its predetermined trajectory across a considerable width of fabric, said last-mentioned means including two pairs of air admission elements extending across the width of the fabric adjacent to the shedding point, said pairs being arranged respectively above and below the shed, each said air admission elements being formed by an air pipe extending outside of the shed and transversely over the warp, the side of said air pipe facing the shed being constructed in a saw-tooth manner, each said air pipe including a plurality of nozzles spaced across the width of the fabric and arranged in the faces of the teeth formed thereon, said nozzles in one of said air pipes of each pair facing in the opposite direction with respect to the nozzles in the other air pipe of the respective pair, and compressed air being supplied to the one of said air pipes of each pair having nozzles facing in the direction of motion of said weft thread to generate an air current in the direction of motion of the traversing weft thread to maintain the same in its predetermined trajectory across the width of the fabric.

9. In a loom for producing woven fabrics of a considerable width having a pneumatic picking system comprising a blow pipe located adjacent the side of the warp, means for admitting a weft thread to said blow pipe, and means for supplying compressed air to said blow pipe whereby said weft thread is propelled through the shed, the improvement consisting essentially of means for maintaining the weft thread in a predetermined trajectory along a considerable width of fabric comprising a pair of air admission elements extending across the width of the fabric adjacent to the shedding point, said elements being arranged respectively above and below the shed, compressed air being supplied to said elements, each said air admission element being formed by an air pipe adjacent the shedding point extending outside of the warp threads and transversely thereto, the side of said air pipe facing the shed being constructed in a saw-tooth manner, said air pipe including a plurality of nozzles spaced across the width of the fabric and arranged in the faces of the respective teeth formed on said air pipe, said nozzles being arranged to face in the direction of motion of said weft thread with the compressed air passing from said nozzle

generating an air current in the direction of motion of the traversing weft thread to maintain the same in its predetermined trajectory across the width of the fabric, said air admission pipes being movable relative to said warp, the positions of said pipes being relative to the warp, the position of said pipes being close to the warp thread during insertion of said weft thread so that the warp threads rest on the backs of the teeth formed on said air admission pipes whereby air can escape from said nozzles to generate said air current.
